UNITED STATES PATENT OFFICE

ALEXANDER H. VADNAIS, OF OSHKOSH, WISCONSIN, ASSIGNOR TO DOUBLE A ALARM COMPANY, INC., OF OSHKOSH, WISCONSIN, A CORPORATION OF WISCONSIN

SPARK PLUG

Application filed June 11, 1928. Serial No. 284,284.

This invention relates to spark plugs and it has among its objects the provision of an improved device of this character arranged to automatically adjust and maintain the 5 sparking distance depending on the temperature conditions so as to secure prompt starting and efficient operation of the engine under normal as well as abnormal temperature conditions.

10 The invention will be best understood from the accompanying drawings, wherein

Fig. 1 is an elevation of a spark plug embodying the invention;

15 Fig. 2 is a plan view of the lower end of of the spark plug of Fig. 1;

Fig. 3 is a side elevation of the lower portion of the spark plug viewed from the right hand side of Fig. 1; and

20 Fig. 4 is a vertical sectional view through the lower portion of the spark plug along the lines IV—IV in Fig. 2.

With ordinary spark plugs it is often difficult to start engines because at the moment of starting the battery voltage is pulled down 25 through the drain of heavy starting current. As a result the ignition apparatus operates at that time with reduced voltage and accordingly a reduced ignition voltage is supplied to the spark plug.

30 By means of my invention this difficulty in starting is overcome by providing a reduced sparking distance at starting while, on the other hand, I retain a fixed and definite normal sparking distance with which the spark 35 gap operates under normal temperature conditions. To this end I provide a thermostatically responsive bridging member so arranged that when cold a part of the gap between the spark plug electrodes is bridged

40 over. This reduces the sparking distance when the spark plug is cold, that is when the engine is cold, and the starting conditions are most difficult. As soon as the engine starts running the full battery voltage is restored, 45 the spark plug warming up in the meanwhile,

The increase of the temperature of the spark plug causes the thermostatically actuated bridging member to restore the normal gap between the spark plug electrodes and the engine runs henceforth with full sparking 50 electrode spacing.

A particular advantage of my arrangement is the fact that under the normal operating conditions the sparking takes place only between the normal fixed electrodes, the thermostatically actuated element being out of the path of the gap at that time, thus being safeguarded against injury by the spark.

Another feature resides in the arrangement of the several electrodes in such a way that no matter how low the temperature of the engine and the parts there will always be a minimum sparking distance between the electrodes so that under no conditions a complete short circuit can take place between 60 the electrodes of opposite polarity.

In the drawings is shown a spark plug construction representing one embodiment of the invention. Such spark plug may consist of a metallic cylindrical shell 1 having a threaded portion 2 adapted to be screwed into the cylinder head, and the customary head 3. Within this shell 1 is mounted an insulating bushing 4 held therein by means of a gland 5 and suitable packing in the customary way. Through the center of the bushing 4 is sealed a lead-in conductor 6 constituting the high potential terminal of the spark plug, the lower end of the conductor constituting one 65 sparking gap electrode 7. The other sparking electrode 8 is formed by the upwardly-bent end of a conductor 9 extending from the lower end of the metal shell 1 of the plug. The conductor 9 is grounded to the cylinder casing and constitutes the other terminal of the sparking gap. The upper end 8 of the grounded conductor 9 and the lower end 7 of the insulated conductor 6 constitute the normal 70 sparking gap as in the ordinary spark plugs used at present.

In order to secure automatic adjustment or reduction of the sparking distance under varying temperature conditions, I employ a thermostatic element in the form of a bimetallic bar 11 having one end secured to the lower end of the cylindrical metal shell 1, for instance by twisting it and welding or riveting it to the lower end surface of the shell at 12. The other end of the bimetallic bar may be folded over itself, as at 13, constituting an enlarged tip adjacent the gap between the main sparking electrodes 7 and 8.

According to the invention one of the two fixed sparking electrodes, in this case the grounded electrode 8, is somewhat offset against the other electrode 7. The thermostatic bar 11 is so arranged that under low temperature conditions its free end tip 13 abuts and rests against the offset portion of the grounded gap electrode 8, a part of the tip extending close to the insulated high potential electrode 7 on the gap. In this way a reduced spark gap is provided between the upper end of the tip 13 and the side of the high voltage sparking electrode 7. When the engine is cold the spark will pass through this reduced gap which is shown best at 15 in Fig. 4. If the temperature rises, the bar 11 turns outwardly restoring the full gap width between the sparking electrodes 7 and 8.

The foregoing arrangement prevents positively short circuiting of the spark gap no matter how low the temperature of the engine is because the minimum spark gap distance is determined by the offset relationship of the two main spark gap electrodes 7, 8. A similar result could be obtained without offsetting the main electrodes by providing a special projecting abutment or stop either on the grounded electrode 8 or on the tip 13 or on both, or by some other arrangement that will suggest itself to those skilled in the art.

My arrangement also secures a definite sparking gap under normal operating conditions because of the fixed positioning of the two main gap electrodes 7 and 8, and thus prevents any disturbance because of excessive gap length when the engine warms up to high temperatures. In other words, my improved spark plug secures a predetermined minimum sparking distance and a predetermined maximum sparking distance. It varies the spark gap only over a limited range between the minimum and maximum width, this range being fixed so as to secure most efficient operation of the engine under low as well as high temperatures. Excessive sparking length that would detrimentally affect the operation of the engine and the danger of bridging the spark gap are thus eliminated while retaining all the advantages of a thermostatically adjustable, varying spark gap.

In the arrangement shown hereinabove the thermostatic bar and the auxiliary bridging

electrode 13 are directly grounded and conductively connected to the metallic shell 1 of the spark gap, this arrangement being advantageous because it avoids double sparking when the electrode tip 13 moves outwardly under rising temperature conditions. However, in some cases such double sparking action may be desired in which case the thermostatic bar 11 may be insulatingly supported on the lower end of the spark plug.

The invention is not limited to the particular details of construction shown hereinabove and many modifications thereof will suggest themselves to those skilled in the art. It is accordingly desired that the appended claims be given a broad construction commensurate with the scope of the invention within the art.

I claim:

1. In a spark plug, a pair of fixed gap electrodes and thermostatically controlled means for partially bridging the gap between the electrodes.

2. In a spark plug, a pair of fixed gap electrodes and thermostatically controlled means for partially bridging the gap between the electrodes, said means being so arranged as to permit variation of the gap length between a fixed minimum and fixed maximum value.

3. In a spark plug, a pair of gap electrodes, a thermostatic element, and a bridging electrode actuated by said thermostatic element to partially shorten said gap.

4. In a spark plug, a pair of gap electrodes and thermostatically actuated means for varying the gap length between a fixed minimum and fixed maximum value.

5. In a spark plug, a pair of gap electrodes and a bimetallic element for varying the gap length between a fixed minimum and a fixed maximum value.

6. In a spark plug, an insulated gap electrode, a grounded gap electrode, and means associated with said grounded gap electrode for varying the active gap length between a fixed minimum and a fixed maximum value.

7. In a spark plug, an insulated gap electrode, a grounded gap electrode, a bridging electrode, and thermostatically actuated means for moving said bridging electrode to vary the gap lengths between said grounded electrode and said insulated electrode, said grounded electrode acting as a stop for limiting the movement of said bridging electrode to secure a minimum spark gap length.

8. In a spark plug, a pair of fixed electrodes, a bridging electrode, and thermostatically actuated means to move said bridging electrode to reduce the spark gap length between said electrodes, one of said fixed electrodes being arranged to stop the movement of said bridging electrode to secure a minimum spark gap length.

9. In a spark plug, a fixed insulating electrode, a fixed grounded gap electrode, a bridg-

ing electrode, and thermostatically actuated means for moving said bridging electrode to reduce the gap length between said fixed electrodes, said grounded fixed electrode being arranged to limit the movement of said bridging electrode so as to produce a minimum spark gap.

In testimony whereof I have hereunto subscribed my name this 7th day of June, 1928.

ALEXANDER H. VADNAIS.
